FIBER COVER FOR FIBER DRUMS

Harold A. Bergstrom, Flossmoor, Ill., assignor to Continental Can Company, Inc., New York, N.Y., a corporation of New York

Filed Jan. 24, 1963, Ser. No. 253,569
21 Claims. (Cl. 229—5.7)

This invention relates to fiber covers for fiber drums and provides a simple, attractive and economically manufactured fiber cover constructed from a plurality of laminated paper disks.

An object of this invention is to provide fiber covers having ends of diverse thickness and depending peripheral skirts of constant thickness, whereby the fiber covers may be used with fiber drums having substantially identical chime and locking band constructions but different weight constructions, without the necessity of redimensioning the fiber drums or the chimes and locking bands associated therewith.

Another object of this invention is to provide a fiber cover having an end, a bead and a skirt constructed from a plurality of circular cover disks of diverse diameters, whereby the fiber cover may be increased or decreased in weight construction by the respective addition or removal of one or a plurality of the cover disks without affecting the dimensions of the bead or the skirt.

Another object of this invention is to provide a fiber cover having a bead and a depending skirt constructed from a plurality of laminated cover disks, at least an outermost one of the plurality of cover disks having a relatively thin disk of extensible paper prelaminated to an outer surface of the outermost one of the cover disks to prevent the cover disks from splitting during fabrication and form a much more attractive cover than hitherto manufactured.

Still another object of this invention is to provide a fiber cover having a bead which is reduced in thickness at a point where the bead seats between a fiber drum chime and an associated locking band, whereby the fiber cover is lockingly wedged between the chime and the locking band, and inadvertent or accidental removal of the fiber cover is precluded.

With the above, and other objects in view that will hereinafter appear, the nature of the invention will be more clearly understood by reference to the following detailed description, the appended claims and the several views illustrated in the accompanying drawings:

FIGURE 1 is a fragmentary vertical sectional view of a fiber drum having a chime, a fiber cover having a bead of reduced thickness seated upon the chime, and a locking band securing the bead between the chime and the locking band, and shows a novel wedge-locking of the fiber cover between the chime and the locking band.

FIGURE 2 is an enlarged fragmentary vertical sectional view of the fiber cover illustrated in FIGURE 1, and shows the relationship between a plurality of relatively thick fiber cover disks of diverse diameters, and a relatively thin disk secured to a surface of each of two outermost cover disks.

FIGURE 3 is a fragmentary top plan view of a fiber cover disk sub-assembly, and illustrates a plurality of circular cover disks of diverse diameters prior to being formed into a fiber cover.

Illustrated in FIGURE 1 is a fiber drum 10 having a body portion 11 and an upper integral inverted bead 12. An upper wall 13 of the body 11 includes an upper peripheral external wall surface 14 and is integrally joined to the inverted bead 12 by an integral shoulder portion 15. A metallic chime 16 is secured to the upper wall 13 of the drum body 11 and includes an upper chime

2

wall 17 in abutment with the upper external wall surface 14 of the body 11. The upper chime wall 17 is inwardly turned to form an integral inwardly directed curl 18.

A fiber cover 20, constructed in accordance with this invention, is seated upon the inwardly directed curl 18 of the chime 16. The fiber cover 20 is secured to the container 10 by a locking band 21 having an upper inwardly directed portion 22 in vertical spaced relation to the curl 18, and terminating in an outwardly directed hem 23.

As is best illustrated in FIGURES 1 and 2 of the drawings, the fiber cover 20 is constructed from a plurality of laminated circular disks of different diameters secured together by a suitable adhesive, and includes an end 24, and a downwardly directed shoulder 25. The shoulder 25 includes a lowermost shoulder portion 26. A bead 27 forms an integral extension of the shoulder 25 and includes a peripherally reduced pinch portion 28 and a peripherally thickened wedge-locking portion 30. The cross-sectional thickness of the wedge-locking portion 30 is twenty-five percent thicker than the thickness of the pinch portion 28, for a purpose to be hereinafter made apparent. The wedge-locking portion 30 terminates in a skirt 31.

The fiber cover 20 includes an outer fiber disk 32 and an inner fiber disk 33. Each of the fiber disks are constructed of kraft linerboard or any other substantially similar paper product. The diameter of the outer fiber disk 32 is greater than the diameter of any of the remaining cover disks, while the diameter of the inner fiber disk 33 is slightly less than the outer fiber disk diameter. The fiber disks 32 and 33 are secured in abutting relationship to one another to form the skirt 31. Between the outer and inner fiber disks 32 and 33 respectively, are outer and inner filler disks 34 and 35 respectively. The outer filler disk 34 has a diameter substantially less than the diameter of either the outer fiber disk 32 or the inner fiber disk 33, and has a peripheral edge 36 in the wedge-locking portion 30. The inner filler disk 35 has a diameter less than any of the above-mentioned cover disks, and has a peripheral edge 37 in the lowermost shoulder portion 26. The cover disks 34, 35 and 33 include respective adhesive-coated surfaces 38, 40 and 41 for securing together the disks 32-35.

A relatively thin, extensible, identical, circular disk 42 of kraft paper is prelaminated to an outer surface 43 of the outer fiber disk 32, and to an outer surface 44 of the inner fiber disk 33 prior to the fabrication of the fiber cover 20. That is, the sheet stock from which the cover disks 32 and 33 are cut have a surface to which extensible kraft paper has been prelaminated.

The disks 32-35, prior to being formed to the configuration of the fiber cover 20 constitute a fiber cover disk sub-assembly 39, as is best illustrated in FIGURE 3.

The fiber cover disk sub-assembly 39 may also be provided with a lining (not shown) of such materials as polyethylene, aluminum foil, polypropylene or Mylar on the exposed surface of the inner disk 33. The lining provides chemical resistance to the underside of the fiber cover 20 to protect it from the drum contents or to prevent water vapor transmission. A lining formed from thermoplastic resin materials such as polyethylene can be used even though the fiber cover 20 is formed under heat and pressure conditions.

The above-mentioned extensible kraft paper disk 42 also prevents splitting and fracture of the fiber cover during fabrication and also enhances the appearance of the completely fabricated fiber cover.

The fiber cover 20 illustrated in FIGURE 1, decreases substantially in cross-sectional thickness radially outwardly from the end 24 to the skirt 31. As heretofore

noted, the bead 27 is also reduced in thickness at the peripheral pinch portion 28. The thickness of the bead 27 at the pinch portion 28 is at least 25% less than the thickness of the bead 27 at the wedge-locking portion 30. The effect of the reduced thickness in the pinch area 28 and the increased thickness of the wedge-locking portion 30 is to create a wedge-locking arrangement between the curl 18 of the body 11 and the upper portion 22 of the locking band 21. In effect, any misuse of the drum 10, such as the drum 10 being accidentally dropped, which would otherwise cause the cover 20 to slip out from between the curl 18 and overlying upper portion 22 of the locking band 21, is precluded.

Furthermore, the downwardly directed shoulder 25 of the fiber cover 20 additionally aids in preventing the cover 20 from being slipped out from between the curl 18 and the locking band 21. The main purpose of the downwardly directed shoulder 25 is to gather extra material in the cover 20 so that when the fiber drum 10 is subjected to a side blow such as can occur upon the dropping of the drum, the drum 10 can deform to a slightly elliptical shape. In the absence of the shoulder 25, the tension which immediately occurs across the long axis of the elliptically deformed drum would cause a flat cover to pull out from underneath the locking band 21. However, the excess material gathered in the downwardly directed shoulder 25 permits material to be present along the long axis, hence, more distortion of the drum 10 is required before a tensile stress is developed in the cover 20 sufficient to pull the cover 20 from between the chime 16 and the locking band 21.

Fiber drums, such as drum 10, are manufactured in numerous sizes and in different weight constructions depending upon the weight of contents that is to be shipped in the drum. Both the rail and motor freight regulations specify the minimum thickness and Mullen test requirements prescribed for specific size and weight construction of drums. Hence, all covers are not made to the same thickness.

The fiber cover 20 illustrated in FIGURE 1 may, for example, be used for shipping 550 pounds of dry products and readily comply with the above-mentioned regulations. In order to make a less expensive cover, the inner filler disk 35 of the fiber cover 20 would be removed, as a result of which, up to 300 pounds of products may be shipped. Furthermore, to increase the particular weight construction of the fiber cover 20 illustrated in FIGURE 1, it would only be necessary to add additional inner filler disks, such as filler disk 35, to the fiber cover 20.

Irrespective of the number of inner filler disks 35 which are added to or removed from the fiber cover 20, the thickness of the wedge-locking portion 30, the pinch portion 28 and the skirt 31 is maintained constant. Because the thickness of the skirt 31 and the bead 27 remain constant, irrespective of the different weight constructions of the cover 20, the height of the chime 16 as well as the width and length of the locking band 21 do not have to be varied.

The fiber cover illustrated in FIGURE 1 is constructed by first cutting the plurality of cover disks from sheet stock to the required diameters. The outer fiber disk 32 and the inner fiber disk 33 are preferably constructed from kraft linerboard. The outer filler disk 34 and the inner filler disk 35 are constructed from solid fiber board, while the relatively thin extensible disks 42 prelaminated to the cover disks 32 and 33 are made from a relatively thin sheet of extensible kraft paper. After the cover disks have been cut as required they are laminated together and formed to the particular configuration of the fiber cover 10 heretofore described.

While a specific fiber cover 20 and a cover disk sub-assembly 39 have been disclosed, various modifications of the above-mentioned structures may be made without departing from the novel concept of this invention.

As an example, a fiber cover constructed in accordance with the disclosure relative to FIGURE 2 would have a weight construction sufficient for shipping 550 pounds of contents and a maximum thickness of .230 inch. Each of the fiber disks is constructed from kraft linerboard having a thickness of approximately .065 inch, while each of the filler disks, made from solid fiber board for example, has a thickness of approximately .050 inch. It should be noted that the thickness of the skirt 31 is the combined thicknesses of the outer fiber disks, i.e., .130 inch, which is the clearance between the inside of a locking band and the outside of a chime of a standard drum. In addition, the caliper of a bead of this example cover is .180 inch, while the caliper of the peripheral pinch portion thereof is .135 inch, resulting in a reduction in caliper at the pinch portion of approximately 25% below the caliper at the wedge-locking portion.

I claim:

1. A fiber cover comprising an end, a shoulder forming an integral extension of said end, a bead integral with said shoulder and terminating in a depending peripheral skirt, said bead including a bight portion between said shoulder and said skirt, said bead bight portion including a peripheral pinch-portion of a lesser thickness than a remaining portion of the bead bight portion adapted when assembled upon a drum between a drum chime and a locking band associated therewith to lockingly wedge the fiber cover upon the drum to preclude accidental removal of the fiber cover from the drum.
2. A fiber cover comprising a plurality of laminated disks and including an end, a shoulder forming an integral extension of said end, a bead integral with said shoulder and terminating in a depending peripheral skirt, said bead including a bight portion between said shoulder and said skirt, said fiber cover radially decreasing in thickness from said end to said skirt, said bead bight portion including a peripheral pinch-portion having a thickness less than the thickness of the bead and adapted when assembled upon a drum between a drum chime and a locking band associated therewith to lockingly wedge the fiber cover upon the drum to preclude accidental removal of the fiber cover from the drum.
3. A fiber cover as defined in claim 2 wherein said plurality of laminated disks are circular and a majority of said disks are of different diameters.
4. A fiber cover as defined in claim 3 wherein said disks include at least an outer disk, an inner disk and an intermediate disk, said inner, outer and intermediate disks forming the end, the shoulder and the bead of said cover, and said inner and outer disks forming said skirt portion.
5. A fiber cover as defined in claim 4 wherein said bead includes a wedge-locking portion between said peripheral pinch portion of said bead and said skirt, said wedge locking portion being thicker than the thickness of the skirt and the thickness of the peripheral pinch-portion of said bead.
6. A fiber cover as defined in claim 5 wherein said intermediate disks terminate within said wedge-locking portion.
7. A fiber cover as defined in claim 6 wherein said plurality of laminated disks includes at least one additional intermediate filler disk, said additional intermediate filler disk terminating at said shoulder whereby the weight construction of said fiber cover may be increased without increasing the thickness of the skirt or the thickness of the bead.
8. A fiber cover as defined in claim 6 wherein said plurality of laminated disks include a plurality of additional identical intermediate filler disks, said plurality of additional identical intermediate filler disks terminating at said shoulder whereby the weight construction of said fiber cover may be materially increased without increasing the thickness of the skirt or the thickness of the bead.
- 70 9. A fiber cover as defined in claim 8 wherein said plurality of laminated disks include a plurality of additional identical intermediate filler disks, said plurality of additional identical intermediate filler disks terminating at said shoulder whereby the weight construction of said fiber cover may be materially increased without increasing the thickness of the skirt or the thickness of the bead.

9. A fiber cover as defined in claim 7 wherein said outer disk overlies said intermediate filler disk, said intermediate filler disk overlies said additional intermediate filler disk and said additional intermediate filler disk overlies said inner disk.

10. A fiber cover as defined in claim 9 wherein each of said inner and outer disks include outermost surfaces having a relatively thin extensible disk laminated thereto.

11. A fiber cover disk sub-assembly comprising a plurality of laminated circular disks, said plurality of disks including a first outer disk, a first intermediate filler disk secured in overlying relationship to said outer disk, a second intermediate filler disk secured in overlying relationship to said first intermediate filler disk and an inner disk secured in overlying relationship to said second intermediate filler disk, each of said plurality of disks being of different diameters, and a relatively thin extensible disk being secured in overlying relationship to each of said inner and outer fiber disks.

12. A fiber cover disk sub-assembly as defined in claim 11 wherein a relatively thin extensible disk is secured in overlying relationship to each of said inner and outer fiber disks.

13. A fiber cover disk sub-assembly as defined in claim 11 wherein the diameter of the outer, inner, first intermediate and second intermediate circular disks respectively decrease in size.

14. A combination of a drum, a locking band, and a fiber cover; said drum including a metallic chime having an upper wall terminating in a curl; said locking band including a portion overlying said curl, said fiber cover including an end, a shoulder, an integral bead and a depending peripheral skirt, said bead including a peripheral pinch portion of reduced thickness between said curl and the overlying portion of said locking band whereby the fiber cover is lockingly wedged against accidental removal from between the curl and overlying locking band portion.

15. A combination of a drum, a locking band, and a fiber cover as defined in claim 14 wherein said fiber cover comprises a plurality of laminated disks, said disks including at least an outer disk, an inner disk and an intermediate filler disk, said inner, outer and intermediate disks forming the end, shoulder and bead of said fiber cover and said inner and outer disks forming said skirt.

16. A combination of a drum, a locking band, and a fiber cover as defined in claim 15 wherein said bead includes a wedge-locking portion between said skirt, and said peripheral pinch portion of said bead, said wedge-locking portion being thicker than the thickness of the skirt and the thickness of the peripheral pinch portion of said bead.

17. A combination of a drum, a locking band and a fiber cover as defined in claim 16 wherein said plurality of laminated disks includes at least one additional intermediate filler disk, said additional intermediate filler disk terminating at said shoulder whereby the weight construction of said fiber cover may be increased without increasing the thickness of the bead and skirt and further enabling the fiber cover to be used with standard drums of diverse weight constructions without redimensioning of the drum, or its associated chime and locking band.

18. A fiber cover comprising a plurality of laminated disks and including an end, a shoulder forming an integral extension of said end, a bead integral with said shoulder

and terminating in a depending peripheral skirt, said fiber cover radially decreasing in thickness from said end to said skirt, said bead including a peripheral pinch-portion having a thickness less than the thickness of the bead and adapted when assembled upon a drum between a drum chime and a locking band associated therewith to lockingly wedge the fiber cover upon the drum to preclude accidental removal of the fiber cover from the drum, at least one of an inner and outer disk of said plurality of disks includes an outermost surface having a relatively thin extensible disk laminated thereto.

19. A fiber cover comprising an end, a shoulder forming an integral extension of said end, a bead integral with said shoulder and terminating in a depending peripheral skirt, said bead including a bight portion between said shoulder and said skirt, said bead bight portion including a peripheral pinch-portion of a lesser thickness than a remaining portion of the bight portion and adapted when assembled upon a drum between a drum chime and a locking band associated therewith to lockingly wedge the fiber cover upon the drum to preclude accidental removal of the fiber cover from the drum, and a wedge locking portion between the peripheral pinch portion of the bead and the skirt, said wedge locking portion being thicker than the thickness of the peripheral pinch portion of said bead.

20. A fiber cover comprising an end panel, said end panel being joined by a shoulder to a bead terminating in a depending peripheral skirt, said shoulder, bead and peripheral skirt defining a generally annular channel substantially U-shaped in cross-section, and a medial portion of said bead being reduced in thickness relative to remaining portions of said bead to either side of said medial portion, and a radially outermost portion of said bead bight portion being thicker than the thickness of the reduced medial portion.

21. The combination of a drum, a locking band and a fiber cover; said drum including a body terminating in a free edge; said locking band including a portion overlying said free edge; said fiber cover including a bead having a bight portion of a predetermined thickness positioned between said free edge and said overlying portion of the locking band, said bight portion including a portion between said free edge and said overlying portion of a thickness less than the distance between said free edge and said overlying locking band portion, and a radially outermost portion of said bead being of a thickness greater than the reduced thickness of said medial bead bight portion.
